ADJUSTABLE JACK POST SUPPORT

William E. Dobson, 1406 Sunset Ave.,
Bellingham, Wash. 98225

Filed Sept. 13, 1966, Ser. No. 3,839

Term of patent 14 years

(Cl. D41—1)

FIGURE 1 is a front elevation of an adjustable jack post support, showing my new design;

FIGURE 2 is a side elevation thereof;

FIGURE 3 is a top plan view thereof;

FIGURE 4 is a side elevation of the jack in an alternate position;

FIGURE 5 is a front elevation thereof; and

FIGURE 6 is a top plan view thereof.

I claim:

The ornamental design for an adjustable jack post support, substantially as shown.
